UNITED STATES PATENT OFFICE.

GEORGE E. MARLATT, OF PASADENA, CALIFORNIA.

TYPOGRAPHICAL MACHINE.

Application filed October 5, 1926, Serial No. 139,719. Renewed July 5, 1928.

My invention relates to typographical machines of the linotype class in which circulating matrices are released by keyboard means from a storage magazine and assembled in a line in the order of their release, the assembled line transferred to a position in front of a mold in which a cast of type metal is made against the line of matrices, and the matrices then returned to their individual channels in the magazine from which they were released.

This disclosure is directed to machines of the "mixer" type in the class above referred to. In this type of machine matrices from two or more magazines may be mixed in a single line in the assembling operation and thereafter automatically separated and distributed into the channels of the magazine in which they belong. The principal objects in view are to provide a machine of simplified and dependable construction and increased matrix capacity. Minor and contributing objects will be disclosed as the description progresses, and it will be understood that the contributing features may be employed in machines of other than the "mixer" type without departing from the scope and spirit of the invention intended to be disclosed. Although but two magazines are illustrated and described, certain features to be described may be employed in connection with machines having more than two magazines. Referring to the accompanying drawings,—

Fig. 1 shows the usual trapeziform magazine overlying the rectangular form of magazine shown in connection with the principal figures of the drawings, and illustrates how the magazine may be widened at its lower end and narrowed at the receiving end in order to provide for additional matrix channels without increasing the total area and weight of the magazine.

Fig. 2 shows the usual trapeziform magazine between a rectangular magazine of less size but with an equal number of channels, and a rectangular magazine as wide as the trapeziform magazine at its receiving end but capable of containing one-third more channels than the usual trapeziform magazine.

Fig. 3 is a right-hand view of the improved machine with the keyboard omitted, the lower portion of the figure being in full lines and the magazines and upper portion in section.

Fig. 4 is a rear view of the upper portion of Fig. 3, being a left-hand view of the upper portion of the machine.

Fig. 5 is a sectional view taken on the line 5—5 of Fig. 4.

Fig. 6 is a sectional view taken on the line 6—6 of Fig. 4.

Fig. 7 is the distributor, being a view of the rear or right-hand side of Fig. 3.

Fig. 8 is a view of the left-hand side of Fig. 7, showing the distributor driving mechanism.

Fig. 9 is section on the line 9—9 of Fig. 3, being a reverse view of the right-hand portion of Fig. 7.

Fig. 10 is a section on the line 10—10 of Fig. 3.

Fig. 11 shows the keyboard added to the front portion of Fig. 3, with the escapement operating reeds shifted to cooperate with the escapements of the lower magazine.

In order that the magazines 10 may be of the rectangular form shown in Figs. 1 and 2, I prefer to employ the distributor and escapement features disclosed in my pending application, Serial No. 139,721, filed October 5, 1926, to which application reference may be had, particularly with regard to the magazine entrance channels 9^a and escapements 27.

As in the prior art, those of the matrices X which are destined for distribution by a lower set of distributor screws are provided with a font-separating notch X¹, but in the present instance the lower set of distributor screws is associated with the upper magazine 10 and the upper set of distributor screws distributes to the lower magazine 10^a. Hence those matrices destined for the lower magazines are supported on a bridge 1 (Fig. 9) from the time they leave the usual distributor box rails 2 until they engage the teeth of the upper distributor bar 3 under control of the distributor conveyor screws, and those matrices which have the notch X¹ will be supported at the lower level on the bridge 1 and will not engage the upper distributor bar 3 but will drop from the end of the rails 2, all in the usual manner.

In the present instance I provide a stub conveyor screw 5 terminating with the bridge 1 and in advance of the first matrix channel 11 in order that it will not interfere with entry of the matrices into the first and succeeding channels. The fourth screw 5 controls the matrices destined for the upper distributor

until they have engaged the teeth of the distributor bar 3. Thus the matrices are controlled at their four corners by four screws and will not twist in position when supported 5 on the bridge 1 as frequently happens when but three screws are employed. This fourth screw carries a gear 8 which is in mesh with an intermediate gear 6 driven by a gear 7 on the upper screw 4. As thus controlled 10 the matrices destined for the upper magazines are insured reliable entrance into the opposed grooves 11 for purposes to be explained, while matrices destined for the lower magazine are carried beyond the bridge 1 15 by means of the usual distributor screws.

It will be noted that only a single distributor box A is employed, no additional box being contemplated in this invention, and the single box may be of usual type. 20 In order that the matrices may be distributed into two magazines with this condition of common and simple construction, I provide as follows: The lugs of the matrices X engage the opposed grooves 11 in the same 25 manner that they engage the usual channels of the magazine. Through the floor of the lower channel I provide two openings 12 and 13 of sufficient size to permit the entrance of the forward and shorter lug of the matrices 30 but small enough to be bridged by the following and longer matrix lug. As each succeeding matrix enters the channel 11 its forward lug enters the opening 13 and lodges until lifted out by means of an escapement 35 element 14 (Fig. 6). The escapement 14 reciprocates once with each rotation of the 40 lower set of distributor screws. To this end an oscillating plate 15 is pivoted beneath the channel 11 on a pivot rod 16 and controls the movement of the escapements 14. The 45 oscillator 15 is actuated by means of a cam 17 on the outer end of one of the distributor screws 1^a, thus insuring movement of the escapements 14 in time with the rotation of the distributor screws. The cam 17 may be 50 provided with an anti-friction roller 18 to prevent wear. The return movement of the oscillator 15 is accomplished by means of a spring 21^a. The two openings 12 and 13 are 55 provided in duplicate in order to prevent two thin matrices overlapping each other in the channel 11 in the event of a distributor stop or other abnormal condition. The lower distributor screws are each provided 60 with two threads, 1^a of which is idle as a conveyor thread and terminates short of the entrance channel 11. Escape of the matrices from the lodgement 12 is so timed with the rotation of the screws that the other thread 65 b on the first screw 1^a will not interfere with the lugs of the matrix as it moves across the reduced portion c of the screw, nor will thread b on the second screw 3^a interfere with the forward lug of the incoming matrix; but when the matrix lodges against a

stop 19 at the end of the channel 11 the threads b will engage the lugs of the matrix and convey it to the appropriate magazine channel. Openings 21 and 22 in the walls of the channel 11 provide clearance for the matrix lugs when the matrix moves laterally from its channel position under control of the distributor screws. When the matrix reaches its magazine channel the idle thread a on the second screw 3^a serves as a bridge for supporting the longer matrix lug when passing the second screw 3^a, the double groove of the screw being of such size and steepness that the longer lug of the matrix can not enter therein. 70

The set of distributor screws for the upper magazine, the associated distributor bar 4^a, and the member 20 in which the grooves 11 are formed are mounted in common on the channel entrance 9 of the lower magazine; therefore ready access may be had to both magazines and their entrances by swinging the entrances to the position shown in dotted lines in Fig. 3. The distributor-driving mechanism as illustrated in Figs. 7 and 8 is of such construction that when the magazine entrances are thus swung, the two distributors will remain properly timed. The driving gear 22^a for the lower set of distributor screws is mounted on the shaft 23 forming the pivot for the distributor entrances, hence the gears on the ends of the screws, 1^a, 2^a, 3^a, remain in mesh with each other and with the driver 22 when the distributor is swung downward as shown in dotted lines; likewise, the driver 22 is integral with a larger gear 24 which remains in mesh with a gear 25 of like size centered with the driving pulley 26, which is associated with the upper distributor-driving mechanism including the driving clutch common to both distributors. The driving clutch illustrated is similar to that described in my Patent No. 1,389,369, hence is not here described in detail. 80

Each of the magazines is intended to contain two fonts or sets of matrices, of different design or size, the matrices of each font being disposed in alternating magazine channels. For example, the first channel would contain a 10-point "e", the second channel an 8-point "e"; the third channel a 10-point "t", the fourth channel an 8-point "t", etc. Therefore, two sets of matrix escapement are provided for each magazine. The escapements are actuated by reeds 31 controlled from a keyboard in usual manner. The contact points 27^a of the lower-magazine escapements are staggered in position as shown, those associated with one font of matrices occupying one position and those associated with an alternating font occupying a relatively offset position; hence, moving the upper ends of the reeds from one to the other of the sets of escapements, selec- 90

tively, will cause a selected font of matrices to be released when the keyboard is operated. The two sets of escapements 28 for the upper magazine are all alike, but they are actuated by two sets of intermediate levers 29 and 30, differing in length according to which of the two sets of escapements they actuate. The ends of the longer levers 29 are offset to a position in front of the shorter levers 30 (Fig. 10), and the contact points 27 of the escapements 28 on the lower magazine are bent in alternating directions to positions in alinement with the contact ends of the levers 29 and 30. It will be apparent that if the upper ends of the actuating reeds 31 are moved from one to another of these four alining positions, any one of four fonts of matrices may be released accordingly. The levers 29 and 30 are pivoted on a rod 32 and raise the upper magazine escapements when the reeds 31 are actuated by the keyboard means, the escapements 28 being pivoted in series on a rod 33 carried by a stationary portion 34 of the assembler entrance throat. A middle portion 35 of this throat is movable on a pivot 36 from the position shown in Fig. 3 to a position in register with the lower magazine for conducting matrices therefrom. A middle portion 37 of the throat partitions move with the throat 35, but an upper portion 38 thereof remains associated with the upper magazine. The rod 32 which supports the escapement elements 29 and 30 is supported in the ends of the partitions 37, and these escapement elements are spaced apart in notches 39 formed in the throat 35, the upper escapements 28 being similarly supported and spaced apart in the stationary portion 34 of the throat. The escapement elements 29 and 30 are supported in notches 40 (Fig. 10) in the edge of a spring-controlled supporting plate 41 pivoted on the throat 35 by means of a rod 42. The upper end of this supporting plate is held substantially spaced away from the throat 35 by means of links 43 which are bent at a right angle beneath an anchoring bar 44, and at their upper end are similarly bent to limit the movement of the plate 41 under pressure of a spring 45. When the throat 35 is lowered to register with the lower magazine, the initial movement thereof will permit the spring 45 to expand and the plate 41 will closely engage the throat and permit the escapement elements 29 and 30 to drop about their pivot 32 and thus remain in a non-interfering position relative to the escapements 27 when the lower magazine is operative. Following the initial downward movement of the throat 35 the lower bent endings of the links 43 will move away from the anchoring bar 44, and when the throat is restored to its upper position the links 44 will limit the movement of the plate 41

and the final movement of the throat will cause the escapement elements 29 and 30 to drag on the plate 41 and thus be raised to operative position. Both the movement of the throat 35 as above described and the movement of the escapement actuating reeds 31 to a selected one of their four operative positions are controlled by means of a crank-handle 46 on a shaft 47 mounted on the lower rigid portion 48 of the assembler throat. A cam 49 is secured to the crank arm 50 and shaft 47 and fits between arms 51 and 52 of a bracket 53 rigidly secured to the movable throat 35. When the longer radius of the cam is in engagement with the arm 52 the throat 35 is thereby held in its upper position, and when the handle 46 is moved to its opposite position the longer radius of the cam will engage the arm 51 and thus move the throat to its lower position. But in either of these positions the handle 50 may be moved a limited distance without affecting the position of the throat, and this limited movement of the handle causes the reeds 31 to move to a selected one of the two positions thereof associated with either magazine. To this end the reeds 31 are guided and spaced apart as usual in a suitable bar 54 secured at opposite ends to supports 55 reaching from a pivotal position on the keyboard. A link 56 joins the support 55 to the cam 49 at an off-center point, and a slight movement of the handle 46 will therefore cause a corresponding movement of the series of reeds 31 for the purpose of placing their ends beneath a selected alternating series of escapement devices. Similarly, the initial movement of the handle 46 when lowering the throat 35 will move the reeds beyond the ends of the escapement devices 29 in time to permit the members 29 and 30 to drop when freed from the supporting plate 41. This is the position of the reeds in Fig. 10. The shaft 47 may extend across and beyond each side of the throat 48 and the bracket 53, cam 49 and link 56 be provided in duplicate at opposite sides of the throat 48. The hinge-pin 36 for the bracket 53 enters a suitable extension 57 of the rigid portion 48 of the assembler throat.

Having thus described my invention and its mode of operation, what I claim as new and desire to secure by Letters Patent is:

1. In a typographical machine, in combination with upper and lower channeled magazines for receiving matrices from individual lower and upper distributors employing sets of conveyor screws, matrices having upper and lower lugs on each edge thereof, upper and lower conveyor screws in each set thereof for engaging the lugs on said matrices, means for causing the matrices destined for the lower distributor to be released successively at a common point from

the upper set of conveyor screws, and means for causing and permitting matrices so released to enter successively between and into engagement with the conveyor screws in 5 the lower set thereof, said latter means comprising an opposed-groove channel through which the matrices are guided in their travel from the upper set of conveyor screws to the lower set thereof, a perforation in the 10 floor of the lower groove of said channel into which a lug on said matrices lodges in advance of the entry of the matrices into engagement with the lower set of conveyor screws and from which it is dislodged in 15 time with the rotation of said screws, and a special form of conveyor screw for permitting the matrices to pass therebetween and then enter into engagement therewith.

2. A combination as specified in claim 1 20 including also a distributor rail on which the matrices are conveyed by the lower set of conveyor screws, an element at the end of said opposed groove channel against which the matrices are stopped in position for 25 engaging said distributor rail, and interruptions in the wall of said channel through which the lugs on said matrices may pass laterally when the matrices are conveyed by said screws from said channel to and 30 into engagement with said distributor rail.

3. In a distributor for typographical machines, in combination, matrices having upper and lower lugs on each edge thereof, a pair of upper conveyor screws for engaging the upper lugs of said matrices and conveying them to individual magazine channels, lower conveyor screw for similarly engaging a lower lug of said matrices, and the specified means whereby the lower lugs on 40 said matrices are permitted to pass between and beyond said pair of upper conveyor screws to a position of engagement with said lower conveyor screw.

4. A combination as specified in claim 3 45 characterized by the fact that each of the conveyor screws therein recited has two threads, one of said threads being active and the other idle, and that the idle thread thereof terminates in advance of the active 50 thread in order to provide clearance for said matrices when passing between the upper conveyor screws.

5. A combination as specified in claim 3 including also means whereby the matrices 55 therein recited are timed with said conveyor screws in their movement for successive individual engagement therewith, said means comprising an opening into which a lower lug on said matrices lodges in advance of 60 its entry between the upper conveyor screws, and from which it is dislodged in time with the rotation of the conveyor screws for proper engagement with the lower screw, an upper and longer lug on said matrices bridging 65 said opening and passing thereover and

into engagement with the upper conveyor screws.

6. In a typographical machine, in combination, a pair of superposed channeled magazines in which matrices are stored and from 70 which they may be released to a delivery throat, matrices in each of said magazines arranged in sets of alternating channels thereof according to font, escapements for releasing said matrices from said channels, 75 reeds for actuating said escapements, a delivery throat to which said matrices are released, and means for selecting between said magazine and between the sets of alternating channels therein for the purpose of releasing 80 matrices of a selected font therefrom, said means comprising a delivery throat movable from one to another of said magazines selectively, a series of intermediate escapement-actuating elements carried thereby for actuating the escapements of the upper magazine and alternating in length for selective employment relative to alternating escapements of the upper magazine, escapements 85 on the lower magazine alternating in form 90 for selective employment relative to alternating channels therein, and a mechanism for moving the escapement-operating reeds selectively from one to another of the alternating forms of escapements on the lower 95 magazine or from one to another of the intermediate escapement-actuating elements 100 of alternating length carried by said delivery throat for releasing matrices from the upper magazine.

7. A combination as set forth in claim 6 including also means for moving the delivery throat from one to another of the superposed magazines and retaining it in a selected position, means for moving the escapement-actuating reeds therewith, and associated and co-acting means for rendering said intermediate escapement-actuating elements active relative to the upper magazine and idle and non-interfering relative to the lower magazine, according to the position 110 of said delivery throat.

8. In a typographical machine having superposed channeled magazines, sets of upper and lower distributor screws associated with each of said magazines for conducting matrices to individual channels thereof, a distributor lift element for separating the matrices one from another and placing them successively into engagement with a first set of distributor screws, a toothed distributor rail from which said matrices are suspended, a bridge for supporting the matrices destined for an upper distributor in order that they may engage the teeth of said distributor rail, and means for insuring the engagement of said matrices with said teeth, said means comprising a fourth distributor screw terminating between the point at which such engagement occurs and the point at which 125

the matrices destined for the lower distributor clear said bridge and are freed from said first set of distributor screws.

9. In a typographical machine, a set of four distributor screws into which matrices are lifted one at a time, one of said screws terminating in advance of the first channel into which said matrices enter when released

from engagement with said screws, in order that said terminating screw will not interfere with the entry of said matrices into said first channel. ¹⁰

Signed at Pasadena, Los Angeles County, California, this 28th day of September, 1926.

GEORGE E. MARLATT.
